CLAIM

The ornamental design for a game table cover, as shown and described.

DESCRIPTION

FIG. 1 is a plan view of a game table cover illustrating one embodiment of the design.

FIG. 2 is an alternate embodiment of the design in FIG. 1, the only difference being the version number; and, FIG. 3 is a representative close-up of a portion of the embodiment of FIG. 2.

The broken line showing of FIG. 3 is for illustrative purposes only and forms no part of the claimed design.
